Primary Examiner — Jennifer O King(74) *Attorney, Agent, or Firm* — Stetina Brunda Garred & Brucker(57) **CLAIM**

The ornamental design for a vehicle charger, as shown and described.

DESCRIPTION

FIG. 1 is a perspective view showing a vehicle charger;

FIG. 2 is a right side view thereof;

FIG. 3 is a top plan view thereof;

FIG. 4 is a front view thereof;

FIG. 5 is a bottom plan view thereof;

FIG. 6 is a left side view thereof; and,

FIG. 7 is a rear view thereof.

In the drawings, the broken line showings are for the purpose of illustrating portions of the vehicle charger that form no part of the claimed design.
